US00D840822S

(12) **United States Design Patent** (10) Patent No.: **US D840,822 S**
(45) Date of Patent: **** Feb. 19, 2019**

(54) **CONTAINER**

(71) Applicant: **SHISEIDO COMPANY, LIMITED**,
Tokyo (JP)

(72) Inventors: **Mao Kimai**, Tokyo (JP); **Akira**
Muraoka, Tokyo (JP)

(73) Assignee: **SHISEIDO COMPANY, LIMITED**,
Tokyo (JP)

(**) Term: **15 Years**

(21) Appl. No.: **35/503,833**

(22) Filed: **Apr. 20, 2017**

(80) **Hague Agreement Data**

Int. Filing Date: **Apr. 20, 2017**
Int. Reg. No.: **DM/097274**
Int. Reg. Date: **Apr. 20, 2017**
Int. Reg. Pub. Date: **Oct. 20, 2017**

(30) **Foreign Application Priority Data**

Oct. 20, 2016 (JP) 2016-22820
Oct. 20, 2016 (JP) 2016-22821
Oct. 20, 2016 (JP) 2016-22822

(51) **LOC (11) Cl.** **09-01**
(52) **U.S. Cl.**
USPC **D9/529**

Primary Examiner — Melanie H Tung

Assistant Examiner — Bao-Yen T Nguyen

(74) Attorney, Agent, or Firm — Andrew F. Young, ESQ.;
Lackenbach Siegel, LLP

(57) **CLAIM**

The ornamental design for a container, as shown and described.

DESCRIPTION

1.1: Front

1.2: Back

1.3: Top

1.4: Bottom

1.5: Left

1.6: Right

1.7: Perspective

1.8: Cross-sectional

1.9: Cross-sectional

Representation **1.8** is, the sectional view cut vertically along the center line of the front view, respectively; Representation **1.9** is, the section view cut vertically along the center line of the left side view, respectively; the shadings indicated by thin lines are intended only to represent the three-dimensional shape of the surfaces of the design.

1 Claim, 9 Drawing Sheets
